UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

SYSTEM OF DISTRIBUTION.

Application filed April 13, 1922. Serial No. 552,241.

My invention relates to systems of distribution and it has special relation to the distribution of energy or power to electric railway systems and the like.

One object of my invention is to sectionalize the working or contact conductor of an electric railway system and to apply voltages of different phases to different sections.

Another object of my invention is to provide a working or supply conductor for an electric railway system, or the like, that is divided into a plurality of independent sections, voltages of different phases being supplied to the successive sections in a predetermined order, preferably a regular rotation of phases.

Another object of my invention is to provide a system of the above-indicated character wherein current-limiting means is connected between the confronting end portions of adjacent sections of the working conductor. A further object of my invention is to provide an electrical distribution system comprising a plurality of independent relatively long sections of a working conductor, which are separated by one or more relatively short sections, together with impedance coils or other means for limiting the current that may flow from one section to another during the passage of an electric locomotive, or the like, along the various sections.

My invention may best be understood by reference to the accompanying drawing,

Fig. 1 of which is a diagrammatic view of an electrical distribution system organized in accordance with my present invention, and

Fig. 2 is a similar view of a modified form of the invention.

Referring to Fig. 1 of the drawing, the system here shown comprises a plurality of supply-circuit conductors 1, 2 and 3 which may constitute a polyphase supply or transmission circuit of the usual character. A plurality of sub-stations 4, 5, 6 and 7, etc., are disposed along the right-of-way, as conditions demand.

The working or contact conductor 8 for the railway system is divided into a plurality of relatively long sections corresponding to the distance between the respective sub-stations. The confronting end portions of the working conductor sections are joined by means of suitable section insulators 9 of any approved type. It should be understood

that the length of each section insulator 9 is sufficient to prevent the current-collecting devices of locomotives traversing the line from simultaneously making contact with adjacent sections of the working conductor 8. In this way, the contact conductor 8 presents a smooth under-running surface for the pantograph or other current collector of an electric locomotive 10 or the like, as the locomotive runs along the usual track rails 11. These rails are grounded in the usual manner, as indicated by the conventional sign 12.

Considering the left-hand section insulator 9, two secondary transformer windings or 15 and 16 are connected between the respective confronting end portions of the adjacent working conductor sections and the common track rail or return circuit 11. The primary transformer winding 17 corresponding to the winding 15 is connected across the supply circuit conductors 1 and 3, whereas the other secondary transformer winding 16 is energized from a primary winding 18 that is connected across a different phase of the supply circuit corresponding to the conductors 1 and 2.

It will be understood that all of the transformer windings 15 to 18, inclusive, are preferably located within the sub-station 4, in accordance with a well-known practice.

Within the remaining sub-stations 5, 6, 7, etc., along the right-of-way, a similar arrangement of transformer windings is effected, although the respective phases of the transmission system are connected in a regular rotation to the secondary transformer windings upon opposite sides of each section insulator 9. For example, considering the sub-station 5, secondary transformer windings 19 and 20 are connected between the respective confronting ends of the corresponding working conductor sections and the common return or rail circuit 11. The primary winding 21, corresponding to the secondary transformer winding 19, is connected across conductors 1 and 2, while the other primary winding 22 is connected to the supply-circuit conductors 2 and 3.

It will be noted that the primary transformer winding 18 in sub-station 4 and the primary transformer winding 21 in sub-station 5 are energized from the same phase of the supply circuit and serve to energize a single section of the working conductor 8.

through the agency of the corresponding secondary transformer windings 16 and 19.

On the other hand, the extreme left-hand section of the working conductor 8 is energized from the supply circuit phase corresponding to conductors 1 and 3, while the

section of the working conductor 8 running between sub-stations 5 and 6 is energized from the third phase of the supply circuit, namely, that corresponding to conductors 2 and 3. In this way, the successive sections of the working or supply conductor 8 are energized by the different phases of the transmission circuit, in accordance with a regular rotation. In other words, the adjacent sections of the working conductor 8 are energized by voltages of phases that differ by equal angles from each other, namely, angles of 60° .

Consequently, as the pantograph or other current collector of the locomotive 10 passes from one section 8 to the next, the difference in voltage between the two adjacent sections and the corresponding tendency for the locomotive to increase in speed is reduced to a relatively small value by reason of the fact that the phases of the voltages impressed upon the adjacent sections of the conductor 8 are only 60° apart.

Reference may now be had to Fig. 2 wherein the system shown comprises the transmission circuit conductors 1, 2 and 3 together with a plurality of sub-stations located along the right-of-way, as previously set forth. However, the working or supply conductor 8 for the railway system, instead of comprising only a series of relatively long sections, includes a plurality of such sections and, in addition, one or more relatively short sections, such as 8^a and 8^b, that are located between and are independent of the relatively long sections. As illustrated, the short sections 8^a and 8^b are insulated from each other and from the adjacent portions of the working conductor 8 simply by suitable air spaces, but it will be understood that any well-known type of section insulator, or the equivalent, may be employed, if desired.

Assuming that the left-hand sub-station illustrated in Fig. 2 corresponds to sub-station 5 of Fig. 1, for example, the secondary transformer windings 19 and 20 are connected to the confronting end portions of the adjacent relatively long sections of the working conductor 8. A common return connection through the track rails 11 is provided as previously described. Furthermore, the primary transformer windings 21 and 22 are arranged and connected to the supply-circuit conductors in the same manner as hereinbefore set forth.

In the system of Fig. 2, however, a current-limiting device, such as an impedance coil 30 or the like, is connected between the confronting end portions of the working-

conductor sections. Furthermore, a plurality of relatively small impedance coils 31 and 32 are shown as connected between the relatively short working-conductor sections 8^a and 8^b and intermediate points of the main impedance coil 30.

It will be understood that, if desired, in lieu of providing the impedance coils 30, 31 and 32, the necessary reactance for limiting the flow of current to a predetermined value may be incorporated in the sub-station trans-formers themselves.

In either case, during the passage of a locomotive pantograph from one relatively long working-conductor section to another, the connection or short-circuit of, first, sections 8 and 8^a; secondly, short sections 8^a and 8^b; and finally, sections 8^b and 8, will cause no injurious results by reason of the reactance that is connected between all pairs of adjacent sections.

In this way, by reason of the overlapping of the successive sections, as illustrated in Fig. 2, a satisfactory running surface may be provided for the current-collecting devices of the locomotives and, at the same time, the circulating currents caused by the passage of such current-collecting devices are maintained below a predetermined value.

To reduce the possible surges of current in the locomotive motors to a relatively small value, in addition to the reactance coils 30, 31 and 32 that are associated with the overhead lines, the locomotive 10 may be provided with two pantographs 35, the lower ends of which are connected by a suitable reactive device 36, the middle tap 37 thereof being connected to the motor-control system in any familiar manner. In this way, as the two pantographs 35 pass along the working conductor 8, even though one pantograph makes contact with the long section 8 and the other pantograph with the short section 8^a, for example, a relatively small variation of current will occur in the motor lead 37 by reason of the interposition of the reactance coil 36, in addition to the current-limiting functions of the reactive devices 30, 31 and 32.

It will be seen that I have thus provided a relatively simple system of distribution for electric railways, whereby the successive sections of a contact conductor are connected to the phases of a polyphase supply circuit in accordance with a regular rotation. I have also provided means for limiting the flow of current from one section to another during the passage of a locomotive, if it is desired to restrict the changes of current at that time to a relatively small value.

I do not wish to be restricted to the specific circuit connections or arrangement of parts herein set forth, as various modifications thereof may be effected without departing from the spirit and scope of my invention.

I desire, therefore, that only such limitations shall be imposed as are indicated in the appended claims.

I claim as my invention:

5. 1. In an alternating-current system of distribution, the combination with a supply conductor comprising a plurality of independent sections, of a plurality of transformer windings respectively connected to the confronting end portions of adjacent sections and energized by voltages of different phases.
10. 2. In an alternating-current system of distribution, the combination with a supply conductor comprising a plurality of independent sections, of a plurality of transformer windings respectively connected to the confronting end portions of adjacent sections and energized in a predetermined order by energy of materially different characteristics.
15. 3. In an alternating-current system of distribution, the combination with a supply conductor comprising a plurality of independent sections, of a plurality of transformer windings respectively connected to the confronting end portions of adjacent sections and energized in regular rotation by energy of materially different characteristics.
20. 4. In an alternating-current system of distribution, the combination with a supply conductor comprising a plurality of independent sections, of a plurality of transformer windings respectively connected to the confronting end portions of adjacent sections and energized by voltages differing substantially sixty degrees in phase, and current-limiting means connected between adjacent sections.
25. 5. In a system of distribution, the combination with a polyphase supply circuit, and a working conductor comprising a plurality of insulated sections, of means for supplying successive pairs of sections with voltages differing in phase by substantially equal angles, and current-limiting means connected between each pair of sections.
30. 6. In a system of distribution, the combination with a working conductor comprising a plurality of independent relatively long sections, of a relatively short section of working conductor located between and independent of said long sections, means for impressing voltages of different phases upon said long sections, and current-limiting means connected between certain of said sections.
35. 7. In a system of distribution, the combination with a working conductor comprising a plurality of independent sections, of means for impressing voltages of different phases upon said sections, and current-limiting means connected between said sections.
40. 8. In an alternating-current system of distribution, the combination with a working
- conductor comprising a plurality of independent sections, of means for supplying alternating-current energy of different phases to said sections in a predetermined order, and current-limiting means connected between each pair of sections.
45. 9. In an alternating-current system of distribution, the combination with a working conductor comprising a plurality of independent sections, of means for supplying alternating-current energy of different phases to said sections in a regular rotation, and current-limiting means connected between each pair of sections.
50. 10. In an alternating-current system of distribution, the combination with a supply conductor comprising a plurality of independent sections, of means for supplying adjacent sections with voltages differing substantially sixty degrees in phase, and current-limiting means connected between adjacent sections.
55. 11. In a system of distribution, the combination with a polyphase supply circuit, and a working conductor comprising a plurality of insulated sections, of means for supplying successive pairs of sections with voltages differing in phase by substantially equal angles, and current-limiting means connected between each pair of sections.
60. 12. In an alternating-current system of distribution, the combination with a supply conductor comprising a plurality of independent sections, of a plurality of transformer windings respectively connected to the confronting end portions of adjacent sections and energized by voltages of different phases, and current-limiting means connected between said end portions.
65. 13. In a system of distribution, the combination with a working conductor comprising a plurality of independent relatively long sections, of a relatively short section of working conductor located between and independent of said long sections, means for impressing voltages of different phases upon said long sections, and current-limiting means connected between each long section and said short section.
70. 14. In a system of distribution, the combination with a working conductor comprising a plurality of independent relatively long sections, of a relatively short section of working conductor located between and independent of said long sections, means for supplying energy of different characteristics to said long sections, and current-limiting means connected between said sections.
75. 15. In an alternating-current system of distribution, the combination with a working conductor comprising a plurality of independent relatively long sections, of a relatively short section of working conductors located between and independent of said

- long sections; means for supplying energy of different phases to said long sections in a predetermined order, and current-limiting means connected between said sections.
16. In an alternating-current system of distribution, the combination with a working conductor comprising a plurality of independent relatively long sections, of a relatively short section of working conductors located between and independent of said long sections, means for supplying energy of different phases to said long sections in a regular rotation, and current-limiting means connected between each pair of sections.
17. In an alternating-current system of distribution, the combination with a working conductor comprising a plurality of independent relatively long sections, of a relatively short section of working conductor located between and independent of said long sections, of means for supplying adjacent long sections with voltages differing substantially sixty degrees in phase, and current-limiting means connected between adjacent sections.
18. In an alternating-current system of distribution, the combination with a working conductor comprising a plurality of independent relatively long sections, of a relatively short section of working conductor located between and independent of said long sections, of means for supplying successive pairs of long sections with voltages differing in phase by substantially equal angles, and current-limiting means connected between adjacent sections.
19. In an alternating-current system of distribution, the combination with a supply conductor comprising a plurality of independent relatively long sections, of a relatively short section of working conductor located between and independent of said long sections, a plurality of transformer windings respectively connected to the confronting end portions of adjacent long sections and energized by voltages of different phases, and current-limiting means connected between adjacent sections.
20. In an alternating-current system of distribution, the combination with a supply conductor comprising a plurality of independent relatively long sections, of a relatively short section of working conductor located between and independent of said long sections, a plurality of transformer windings respectively connected to the confronting end portions of adjacent long sections and energized in a predetermined order by energy of materially different characteristics, and current-limiting means connected between adjacent sections.
21. An alternating-current railway system comprising a polyphase supply circuit, a working conductor comprising a plurality of main sections and a plurality of auxiliary sections, means for energizing said main sections from successive phases of said supply circuit, each pair of main sections being separated by one or more intermediately located auxiliary sections, impedance means joining said main and intermediate sections, and a locomotive having two current-collecting devices joined by a balance coil, said current-collecting devices bearing on said main and auxiliary sections successively as the locomotive advances.
22. An alternating-current railway system comprising a polyphase supply circuit, a working conductor comprising a plurality of sections, means for energizing said sections from successive phases of said supply circuit, and a locomotive having two current-collecting devices joined by a balance coil, said current-collecting devices bearing on said sections successively as the locomotive advances.
23. A locomotive having two current-collecting devices joined by a balance coil.
- In testimony whereof, I have hereunto subscribed my name this 11th day of April, 1922.
- CHARLES LE G. FORTESCUE.
